UNITED STATES PATENT OFFICE

SOLOMON KARPEN, OF CHICAGO, ILLINOIS, AND FRANK KASPAR, OF HUNTINGTON PARK, CALIFORNIA, ASSIGNEES TO S. KARPEN & BROS., OF CHICAGO, ILLINOIS, A CORPORATION OF WEST VIRGINIA

MATTRESS AND PROCESS OF MANUFACTURE

Application filed April 18, 1931. Serial No. 531,166.

This invention relates particularly to mattresses of the type employing a filling comprising a spring structure and suitable wadding material thereover, such as cotton, hair, 5 or the like.

The primary object is to provide an improved mattress and an improved method of manufacturing mattresses.

In accordance with the improved method, 10 in which a quilted boxing is preferably employed, the edge-portions of the boxing are joined to inner top and bottom cover-sheets, which may be of duck, or other cheap lining material; the filling is stuffed or introduced 15 into the casing thus formed, the opening being closed after the introduction of the filling; an edge-roll is formed by stitching through the corner portions of the casing and the interposed filling material; and 20 top and bottom finish-fabrics are then applied to the stuffed casing having the previously formed edge-roll portions, and the edge-portions of said fabrics are then sewed to the edge-portions of the finish-fabric of 25 the boxing at the corners of the mattress, thus completing the mattress.

The filling material may be introduced into the casing through an open end of the casing; or the filling may be introduced 30 through an open top side of the casing.

Where the factory is equipped with a suitable machine for stuffing the filling through the end of the casing, this method of introducing the filling is preferred.

35 The invention is shown in the accompanying drawings, in which—

Figure 1 is a broken vertical longitudinal sectional view of a mattress casing comprising a quilted boxing and top and bottom lining-sheets secured to the marginal portions of the boxing, one end of the casing being left open to permit stuffing; Fig. 2, a broken vertical sectional view showing such a casing in stuffed condition; Fig. 3, a broken view, partly in section and partly in elevation, illustrating the manner in which edge-rolls are formed at the corner portions of the mattress before the top and bottom finish-fabrics are applied; Fig. 4, a similar 50 view showing the mattress after the top and

bottom finishfabrics have been applied and sewed to the marginal portions of the boxing; Fig. 5, a broken transverse vertical section illustrating a modification in which the casing is stuffed through an open side, the casing 55 comprising a quilted boxing and top and bottom lining-fabrics; Fig. 6, a broken view, partly in section and partly in elevation, illustrating a finished mattress, according to a slight modification wherein a modified 60 form of boxing is employed; and Fig. 7, a similar view, showing another modification of the boxing.

In the construction illustrated in Figs. 1-4, A designates a mattress casing comprising a quilted boxing 1 and top and bottom lining-sheets 2 having their marginal portions secured to the marginal portions of the boxing by stitches 3; A', A' designate top and bottom finish-fabrics applied, as a 65 final step, in finishing the mattress; and B designates a filling which comprises an inner spring structure B' and layers B² of filling material over the spring structure.

In the illustration given in Figs. 1-4, the 70 boxing 1 comprises simply a strip of finish-fabric 1^a and a layer of cotton 1^b.

The boxing is prepared by sewing the layer of cotton and the fabric together by longitudinal lines of stitching 1^c (Fig. 4) and 75 vertical lines of stitching 1^d, adapted to give the appearance of vertical flutings.

It has been found unnecessary to employ a lining-fabric in conjunction with the finish-fabric in forming the boxing. In other words, the layer of cotton and the finish-fabric may simply be quilted together by a sewing or embroidering operation.

Assuming a casing or sack to have been formed in the manner illustrated in Fig. 1, the filling B is introduced through the open end of the casing, preferably by means of a stuffing machine. Thereafter, the end-portions of the boxing corresponding with the open end of the casing are sewed to the corresponding end-margins of the top and bottom fabrics 2.

This leaves the structure in the condition shown in Fig. 2, where the inner spring structure B' is shown as comprising a series 100

of fabric-cells 4 and upholstery springs 4^a contained in the fabric-cells.

It is preferred to include with the filling edge layers of cotton 5 which are interposed between the quilted boxing and the adjacent rows of springs.

After the stuffing operation, the corner portions of the mattress are operated upon to form edge-rolls. This is done by stitching through the corner portions of the mattress, as indicated in Figs. 3 and 4. This stitching provides ties 6 which form the edge-rolls 7.

Where a design is worked into the boxing in the quilting operation, it is preferred to have the exposed loops of the ties 6 register advantageously with points of intersection, apices, or the like, of the quilting of the boxing. Thus, in Fig. 4, the exposed loops of the ties 6 are shown registering with the points of intersection of the vertical lines of stitches 1^a and the horizontal line of stitches 1^b.

After the edge-rolls have been formed as shown in Fig. 3, in which operations the edge-roll forming stitches pass wholly through the boxing, the top and bottom finish fabrics A' are placed in position and sewed to the edge-portions of the boxing. In this operation, which may be performed by means of a suitable sewing machine, a corner tape 8 may be applied. The stitchings at the corners of the mattress are designated 8^a.

It will be observed that while it is desirable to use care in properly spacing the exposed loops of the ties 6, it is unnecessary to use any particular care where the loops engage the outer surfaces of the top and bottom lining-sheets 2.

After the finish-fabrics A' have been applied, first at one side and then at the other side of the mattress, the result is a well-stuffed mattress of pleasing appearance, uniform in its workmanship.

As shown in Fig. 4, the mattress presents half-rolls at the corners. That is, the portions of the rolls which show exteriorly are at the upper and lower portions of the boxing. On the other hand, the top and bottom finish-fabrics are unbroken in their contour, the result being to give a pin-cushion corner effect, with nicely rounded corners for the top and bottom finish-fabrics.

The method renders it unnecessary to introduce any filling between the top and bottom lining-fabrics 2 and the top and bottom finish-fabrics A'. However, it is optional with the maker whether any filling shall be introduced between the top and bottom lining-fabrics and the top and bottom finish-fabrics.

In the modification shown in Fig. 5, A^a designates a casing like that shown in Fig. 1, except that the boxing 1 is of endless

form, and the top lining-fabric 2 is left unattached, except at one edge. This permits the filling B to be introduced through the open top of the casing. Thereafter, the casing may be closed; the edge-rolls may then be formed; and the top and bottom finish-fabrics may then be applied.

In the modification shown in Fig. 6, the construction is similar to the construction already described, except that the casing 75 designated A^a is provided with a border-boxing 9 comprising an outer fabric 9^a, an adjacent lining fabric 9^b, and a layer of cotton 9^c, all quilted together by lines of stitching 9^d.

Thus, it will be noted that the lining-fabric in this instance is immediately adjacent the inner surface of the finish-fabric. In this case, the lining-fabric 9^b of the boxing may have its margins sewed to the top and bottom lining-fabrics designated 2^a; the corner stitching to form the edge-rolls may then be performed; and the top and bottom finish-fabrics, also designated A', may be applied.

In the modification shown in Fig. 7, the casing A^a is provided with a boxing designated 10. This boxing is of the more usual form, comprising a finish-fabric 10^a, an adjacent layer of cotton 10^b, and a lining fabric 10^c, all quilted together by stitchings 10^d.

In this instance, the outer fabric 10^a of the boxing is shown sewed to the top and bottom lining-fabrics, designated 2^b. After the stuffing operation, the edge-rolls are formed in the manner previously described, after which the top and bottom fabrics A' are applied and sewed to the edge-portions of the fabric 10^a.

In any case, it is unnecessary to cut the top and bottom lining-fabrics free from the finish-fabric of the boxing before sewing the top and bottom finish-fabrics of the mattress to the margin of the finish-fabric of the boxing.

By reference to Figs. 6 and 7, it will be understood that, before applying the top and bottom finish-fabrics A', it would be possible to cut the top and bottom lining-fabrics between the corner ties and the seams at the corners of the casing. However, this is unnecessary and it is preferred not to follow this course.

The process described enables a unit comprising a casing and a filling to be constructed in such manner that the casing will be particularly well stuffed, and the edge-rolls at the corners to be well formed in a facile manner, the outer ends of the loops of the ties forming the edge-rolls being accurately registered with desired points in the stitching which forms the quilting of the boxing; and the process enables the mattress to be finished in a uniform manner by ap-

plying the top and bottom finish-fabrics and sewing them evenly to the edge-portions of the boxing. The resultant construction is one in which the mattress has inner and outer top and bottom fabrics, providing a durable structure. If desired, filling material B³ may be introduced at the corner portions of the mattress between the top and bottom lining-sheets and the top and bottom

10 finishing-fabrics.

The foregoing detailed description has been given for clearness of understanding only, and no unnecessary limitations should be understood therefrom, but the appended

15 claims should be construed as broadly as permissible, in view of the prior art.

What we regard as new, and desire to secure by Letters Patent, is:

1. In the manufacture of mattresses, the

20 steps which comprise: forming a unit comprising top and bottom lining-sheets, a boxing sewed to the lining-sheets, and a filling interposed between said lining-sheets;

25 stitching the corner-portions of the unit to form edge-rolls, the stitches extending through said boxing and through said lining-sheets; and applying top and bottom

finish-fabrics and sewing their edge-portions to the edge-portions of the boxing.

2. In the manufacture of a mattress, the method which comprises: forming a casing comprising a quilted boxing, and top and bottom lining-sheets; introducing a filling

35 into the casing after the casing has been formed, but before it has been wholly closed; completing the closing of the casing; stitching edge-rolls through the corner-portions of the unit thus described; and applying top

30 and bottom finish-fabrics and sewing their edge-portions to the edge-portions of the boxing.

3. A mattress making process, comprising: sewing to the edge-portions of the finish-

45 fabric of a pre-formed boxing edge-portions of top and bottom lining-sheets to form a casing having an open end introducing into the casing a filling and closing the opening therein; forming corner edge-rolls on the

50 unit thus described by stitches which extend through the finish-fabric of the boxing, the lining-sheets, and the interposed filling material; and applying top and bottom finish-

55 fabrics to the unit and sewing the edge-portions thereof to the edge-portions of the finish-fabric of the boxing.

4. A mattress comprising a unit which comprises a casing consisting of a boxing and lining-sheets united thereto, and a filling

60 within the casing comprising a spring-structure and overlying and underlying layers of filling material; ties extending through the boxing and through the lining-fabrics

65 and forming edge-rolls at the corner-portions of the unit; and top and bottom finish-fab-

rics unconnected with said ties and having their edge-portions sewed to the edge-portions of the boxing.
